UNITED STATES PATENT OFFICE.

JACOB EBERHARDT, OF CHICAGO, ILLINOIS.

SASH-FASTENER.

SPECIFICATION forming part of Letters Patent No. 398,884, dated March 5, 1889.

Application filed January 7, 1889. Serial No. 295,658. (No model.)

To all whom it may concern:

Be it known that I, JACOB EBERHARDT, residing at Chicago, in the county of Cook and State of Illinois, and a citizen of the United States, have invented a new and useful Improvement in Sash-Fasteners, of which the following is a specification, reference being had to the accompanying drawings, in which—

Figure 1 shows my device applied in position for use with a window-sash, the meeting-rails of the sashes and the window-panes being in section. Fig. 2 is an under side view of the device in position to allow the window-sash to be moved, and showing also in dotted lines its locking positions. Fig. 3 is a section at line 3 3 of Fig. 2. Fig. 4 is a bottom view of the plate, one end being broken off. Fig. 5 is a section at line 5 5 of Fig. 4. Fig. 6 is a modification, being a section through a portion of a window-sash and casing, looking down, some portions of my device being also in section.

This invention relates to window-sash fasteners, and has for its object to construct a fastener that will be simple in construction, easily operated, and will hold the window-sash in any desired position; and its nature consists in the several parts and combinations of parts hereinafter described, and pointed out in the claims as new.

In the drawings, A represents a cam, one edge of which is roughened or serrated, as shown. At the side opposite to this roughened or serrated edge is a short knob or handle, a, on one face of the cam A.

B is a metal plate provided, as shown, with a semicircular slot, b, through which the knob or handle a projects when the parts are in position for use. The cam A and plate B are pivoted together by the pivot c.

d is a spring-actuated pin placed in a socket in the cam A between the slot b and pivot c, as shown in Fig. 3.

e is a curved groove cut in the under face of the plate B in position to receive the head of the pin d when the plate and cam are in position. This groove is cut deeper at its ends than at its center, or double inclined, as shown in Fig. 5. At the center of this groove

50 is a slight depression, f.

g is a metal strip having a roughened or

serrated face and secured to the side of the window-sash.

In use the plate B is secured to the side of the window-casing by screws or otherwise, 55 the cam A entering a recess cut in the window-casing, such recess being of sufficient size to allow the cam to be turned freely. The side of the recess next to the window is to be cut away, so that the serrated edge of 60 the cam can project and come in contact with the roughened or serrated metal strip g, which is applied to protect the sash, but which in the cheaper forms of sashes may be omitted, or when the sash is counterbalanced. 65

When it is desired to raise or lower the sash, the cam is moved by means of the knob or handle a until such knob or handle is at the center of the slot b, when the cam will be in the position shown in full lines in Fig. 70 2 and out of contact with the strip g or the sash. When in this position, the pin d will by the action of the spring be forced into the depression f and hold the cam against accidental movement. When the window has been 75 opened as desired, the knob or handle a is moved toward the end of the slot b until it brings the cam against the sash or strip g and holds the sash firmly. By reason of the peculiar shape given to the groove e, in which 80 the head of the pin d slides, the cam cannot easily be shifted from the position in which it is set without taking hold of the knob or handle a or giving the sash a slight reverse movement. When the strip g is omitted, a 85 simple roughing of the cam will be sufficient.

In Fig. 6 I have shown a modification for an upper sash in which the cam A is secured to a rock-shaft which runs through the window-casing, the cam in this construction acting against the edge of the sash instead of against its face, or against a strip, as g, secured to the sash. This rock-shaft is operated by a crank, to which the spring-actuated pin d is secured. A plate is attached to the 95 face of the casing, which plate is provided on its outer face with the groove e, having the central depression, f, into which the pin d on the crank projects, as and for the purpose already set forth.

100 What I claim as new, and desire to secure by Letters Patent, is as follows:

1. The cam A, provided with a handle, *a*, in combination with the plate B, having a curved groove, *e*, and the spring-actuated pin *d*, substantially as and for the purpose specified.
2. The cam A, having a serrated edge, and plate B, having a curved groove, *e*, having its bottom oppositely inclined toward its ends, and a central depression, *f*, in combination with the spring-actuated pin *d*, substantially as and for the purpose specified.

JACOB EBERHARDT.
